UNITED STATES PATENT OFFICE.

ARTHUR H. BALLARD, OF SAN FRANCISCO, CALIFORNIA, ASSIGNOR TO BALLARD OIL BURNING EQUIPMENT COMPANY, OF BOSTON, MASSACHUSETTS, A CORPORATION OF MASSACHUSETTS.

ROTARY OIL BURNER.

Application filed December 26, 1918. Serial No. 268,875.

To all whom it may concern:

Be it known that I, ARTHUR H. BALLARD, of San Francisco, in the county of San Francisco and State of California, a citizen of the United States, have invented a new and useful Improvement in Rotary Oil Burners, of which the following is a full, clear, and exact description, reference being had to the accompanying drawings, 10 forming a part of this specification, in explaining its nature.

The present invention relates to an improvement in rotary oil burners employing a centrifugal atomizer or atomizing cup for 15 reducing the oil into a fine spray.

It is among the objects of my invention to obtain an improved means or device by which the oil is fed and applied to the interior of the cup, and to obtain a quicker 20 and more effective control of the oil in its relation to the cup than has hitherto been obtained, both for excluding the oil from the cup and its admission to it.

According to practices hitherto employed 25 the oil has still continued to flow into the cup after the valve controlling the feed has been closed and rotation of the cup stopped. The reason for this is that dependence has been placed either in whole or in part upon 30 gravity for effecting the feed of the oil, and as the cut-off valve is placed some little distance away from the cup in the pipe connection, the oil within the pipe forward of the valve will continue to flow into the cup 35 after the valve has been closed. This after flow of oil is very slow owing to atmospheric pressure, but continues nevertheless for an appreciable length of time and results in filling the cup with an undesired amount of 40 oil, daubing it and supplying it in too great excess to become properly atomized when the cup is set in operation, thereby interfering with a quick lighting of the burner.

Apart from the objection just referred to, 45 a further disadvantage overcome by my invention is that when the cut-off valve is opened for supplying oil to the cup the oil must fill the pipe beyond the cut-off valve between it and the cup before the burner 50 can become effectively lighted, which prevents a quick lighting of the burner.

A still further object of my invention is to provide an improved means by which the oil may be applied to the cup, my purpose being to apply the oil in a relatively 55

thin layer or layers irrespective of the amount of oil admitted into the cup. When thus applied the progression of the oil through the cup toward the outer atomizing edge thereof will be as a relatively thin cylinder of oil which will break from off the outer atomizing edge of the cup evenly and into a very fine spray.

My invention can best be seen and understood by reference to the drawings, where 60 the device embodying my invention is applied to an atomizing cup of well known character and in which—

Figure 1 is a cross vertical section.

Fig. 2 is a section on the line 2—2 of 70 Fig. 1, and

Fig. 3 is a cross section showing a slight modification in construction.

Referring to the drawings:—

1 represents a rotary atomizing cup of 75 any well known character, which is mounted upon a stem 2 connecting with any suitable mechanism (not shown) for rotating it and the cup.

3 is a stationary oil delivery pipe through 80 which the oil is introduced into the cup. Within this pipe is arranged a cut-off valve 4, and the pipe connects with any suitable source of oil supply (not shown). The oil delivery pipe connects within the cup with 85 a stationary upturned, troughlike receptacle 6 capable of maintaining a head of oil within it when the cut-off is closed and the delivery pipe beyond said cut-off is in a position where oil therein will gravitate therefrom. 7 represents the bottom of the receptacle adjacent to which the delivery pipe connects, 8, 8 the sides and 9, 9 the ends of the receptacle. The top of the receptacle facing the interior of the cup is open. The 90 receptacle is preferably made V-shaped as shown, the diverging sides being angularly arranged.

The preferable disposition of the receptacle or trough or the upward extension of its sides is such that the top edges 10 of its sides; and by this is meant preferably both sides; terminate short of the interior face of the atomizing cup, an appreciable space separating the same. The ends 9, 9 of the 100 receptacle, however, present top edges 11 which conform to the shape of the interior of the cup and have an extension just short of engagement therewith so as to make a substantially tight joint without interfering 110

with the free rotation of the cup. The receptacle is preferably arranged adjacent the interior end or bottom of the atomizing cup and extends some appreciable distance into the same so that the receptacle is capable of holding a considerable amount of oil and the top edges 10 of its sides will be of some appreciable length. The arrangement of the receptacle is also preferably such that the top side edges 10 will extend on lines substantially parallel with the axis of the cup.

Preferably arranged upon the bottom of the cup and extending longitudinally thereof is a downwardly-depending oil-distributing wing 12. This wing extends the full length of the receptacle.

The operation is as follows: Oil admitted through the delivery pipe will first fill the oil-receiving receptacle or trough 6. As the inflow of oil continues the oil will flow out of the trough over the top edges 10 of its sides and, if the inflow of oil is not excessive, as the oil flows over the edges 10 it will cling to the trough by capillarity and flow down the sides onto the oil-distributing wing 12 and drop off the same into the interior of the cup, the same effect prevailing if the wing were eliminated (as in Fig. 3), for in such case the oil would drop off the bottom of the receptacle or trough instead of the wing. I prefer, however, to employ the wing. As the inflow of oil into the receptacle is increased, and especially as the oil tends to become heated and more fluid during the operation of the device, instead of flowing downwardly over the sides of the receptacle it may flow over the top side edges 10 thereof and drop directly onto the interior surface of the cup, although in such case some oil will at any rate follow the sides of the receptacle and drop off the oil-distributing wing. In any event the oil will be applied to the cup in a comparatively thin, even layer or layers, and such application may be at one or more points depending upon the fluidity of the oil and the rate at which it is being introduced into the oil-holding receptacle.

Apart from the manner of application of the oil to the interior of the cup, in accordance with the objects of my invention, it will be seen that when the valve is closed for shutting off the supply of oil, only that amount of oil within the receptacle capable of flowing over the dam provided by the side edges of the receptacle will be admitted to the interior of the cup and this amount of oil being very slight will be taken care of by the rotation of the cup which continues, in practice, to rotate by reason of its momentum for an appreciable time even after the mechanism for rotating it has been shut off.

A further advantage in accordance with the objects before referred to is that after

the closure of the oil supply valve the delivery pipe beyond the same together with the receptacle will remain filled with oil so that when the burner is started only a sufficient amount of oil need be introduced into the receptacle to cause a flow of oil over the top edges of its sides. As such introduction of oil need be very slight and as the rising of the level of the oil within the receptacle is practically instantaneous with the opening of the valve, a very quick starting of the burner can be effected.

While I have stated that the top edges of the sides of the receptacle are spaced from the interior surface of the cup sufficiently to enable oil rising within the receptacle to flow over these edges, yet the edges may be extended so far that the oil may not freely pass over the same from within the receptacle excepting when the oil rises so high within the receptacle as to engage the surface of the cup, when it will be carried off by a wiping action.

Having thus fully described my invention, I claim and desire to secure by Letters Patent of the United States:—

1. In a burner of the type specified, the combination with a rotary atomizing cup, of a stationary delivery pipe through which oil is introduced into the cup, a cut-off in said pipe, a stationary upturned receptacle within the cup with which the delivery pipe connects and into which the oil is initially fed, said receptacle being arranged whereby it will maintain a head of oil within it when the cut-off is closed and the delivery pipe beyond said cut-off is in a position where oil therein will gravitate therefrom, said receptacle presenting also an edge over which the oil will pass into the cup from the head of oil maintained within the receptacle during the feeding of the oil and rotation of the cup.

2. In a burner of the type specified, the combination with a rotary atomizing cup, of means for feeding oil to the interior of the cup, the same comprising a stationary delivery pipe, a cut-off in said pipe, a stationary upturned receptacle within the cup with which the delivery pipe connects and into which the oil is initially fed, said receptacle being arranged whereby it will maintain a head of oil within it when the cut-off is closed and the delivery pipe beyond the cut-off is in a position where oil therein will gravitate therefrom, said receptacle presenting also an edge over which the oil will pass into the cup from the head of oil maintained within the receptacle during the rotation of the cup and feeding of the oil.

3. In a burner of the type specified, the combination with a rotary atomizing cup, of a stationary delivery pipe through which oil is introduced into the cup, a cut-off in said pipe, a stationary receptacle within the cup

with which the delivery pipe connects and into which the oil is fed, said receptacle being arranged whereby it will maintain a head of oil within it when the cut-off is closed and the delivery pipe beyond said cut-off is in a position where oil therein will gravitate therefrom, said receptacle presenting also one or more edges by which oil flowing out of said receptacle during the rotation of the cup and feeding of the oil will be directed onto the interior surface of the cup in a relatively thin layer.

4. In a burner of the type specified, the combination with an atomizing cup, of means for feeding oil into the cup, the same comprising in part an upturned receptacle into which the oil is fed and capable of maintaining a head of oil within it, the top of said receptacle co-operating in part with the interior surface of the cup to form a substantially tight joint therewith and presenting in part an edge spaced from the interior surface of the cup whereby oil rising within said receptacle from the head of oil maintained therein may be directed out of the receptacle and deposited upon the surface of the cup in a substantially thin layer.

5. In a burner of the type specified, the combination with an atomizing cup, of means for feeding oil into the cup, the same comprising in part an upturned receptacle into

which the oil is fed and capable of maintaining a head of oil within it, the top of said receptacle co-operating in part with the interior surface of the cup to form a substantially tight joint therewith and presenting in part an edge extending on a line substantially parallel with the axis of said cup and by which edge oil rising within the receptacle from the head of oil maintained therein may be directed out of the receptacle and deposited upon the interior surface of the cup in a relatively thin layer.

6. In a burner of the type specified, the combination with an atomizing cup, of means for feeding oil into the cup, the same comprising an upturned substantially V-shaped receptacle located within the cup and capable of maintaining within it a head of oil, said receptacle presenting sides and ends, the ends of said receptacle at the top edges thereof co-operating with the interior surface of the cup to form therewith a substantially tight joint, the sides of said receptacle at the top edges thereof being spaced from the interior surface of the cup and extending on lines substantially parallel with the axis of the cup, said receptacle presenting also a bottom edge likewise extending on lines substantially parallel with the axis of the cup.

ARTHUR H. BALLARD.
